UNITED STATES PATENT OFFICE.

JOSEPH MARKEL AND IRVING P. SMITH, OF BUFFALO, NEW YORK, ASSIGNEES TO
BUFFALO CHANDELIER CORPORATION, OF BUFFALO, NEW YORK, A CORPORATION
OF NEW YORK

ELECTRIC-LIGHT FIXTURE.

Application filed September 15, 1924. Serial No. 737,734.

To all whom it may concern:

Be it known that we, JOSEPH MARKEL and IRVING P. SMITH, citizens of the United States, residing at Buffalo, in the county of Erie and State of New York, have invented a new and useful Improvement in Electric-Light Fixtures, of which the following is a specification.

This invention relates to improvements in electric light fixtures and more particularly to a combination fixture of the wall bracket type.

The principal object of the invention is to provide a combination fixture of exceedingly simple construction and compact form and which may be economically produced.

A further object is to provide a combination fixture having its parts of such form and arrangement that pleasing artistic effects may be achieved.

An embodiment of the invention is illustrated in the accompanying drawings, wherein:

Figure 1 is a side elevation of the improved fixture.

Figure 2 is a sectional view.

Figure 3 is a front elevation thereof.

The body of the fixture is in the form of an integral casting having a hollow base 1 which is circumscribed by a flange 2. The base 1 may be of any desired outline and is adaptable to varying artistic effects while, in point of utility, it provides for the attachment of the fixture to the wall W by any suitable means, as for example an attachment screw 3 passed through an opening in said base and engaging an internally threaded sleeve 4 fitted in said wall, the screw 3 having at its outer end a clamping head 5 which engages the outer face of the base 1 and holds the fixture with its flange 2 resting against the wall. The base is formed in its lower portion with a forwardly projecting tubular neck 6 which terminates in an upright casing 7 within which is mounted the usual insulating sleeve 8 which encloses the lamp socket and its associated parts, the lamp as 8^a projecting from the sleeve 8 and said sleeve being directly supported upon the bottom of the casing 7

and being removable from said casing through an opening 9 in the top of said casing. Below the neck 6 the base is formed with a bottom 10 which has a central opening 11 and adjacent said opening is provided with an internal annular shoulder 12 which directly supports an electric socket 13 of any suitable or usual construction, the socket 13 being confined in position by an overlying bar 17 which by screws 18 passing through the ends thereof is secured to lugs 19 formed internally of the base. The socket 13 is provided for co-operation with a plug 14 carried by the cord 15 of some electrical household accessory to which current is to be supplied. The arrangement is such that the socket 13 is wholly enclosed in the base 1 and does not project outward beyond the opening 11, while the bottom 10 by which the socket is supported preferably immediately adjoins the bottom of the casing 7.

The wires for the lamp 8^a and the socket 13 are enclosed within the base and pass through a sleeve 16 fitted in the wall W, the wires for the lamp passing through the neck 6 which serves for the support of the casing 7. The casting 1 serves as the direct support for the sleeve 8 and the parts enclosed thereby and for the socket 13 and in turn is directly secured to the wall W from which it follows that the casting may be made of minimum size and that complete freedom is given as to its design, from an artistic standpoint. The fixture is therefore specially adapted for use in bathrooms or boudoirs where compactness and artistry of design are required and provides for the use of an electrical household accessory without the necessity of removing the lamp 8^a in order to make the connection.

Having fully described our invention, we claim:

An electric light fixture comprising an integral casting formed with a hollow wall engaging base having means of direct attachment to a supporting wall, a short tubular neck projecting forwardly from said base, and an upright lamp casing carried by said neck and having a bottom which

serves as the direct support for the lamp which said socket is accessible for the completion of an electrical connection.
socket and its associated parts, the base
having a bottom below said neck and adja-
cent the bottom of the casing, and a socket
5 wholly enclosed within said base directly
supported on the bottom thereof, the bottom
of said base having an opening through
In testimony whereof we affix our signatures.

JOSEPH MARKEL.
IRVING P. SMITH.
